UNITED STATES PATENT OFFICE.

JOHAN SKINDERVIKEN, OF CHICAGO, ILLINOIS, ASSIGNOR OF ONE-HALF TO OLAF E. RAY, OF CHICAGO, ILLINOIS.

ELECTRIC SAFETY SYSTEM FOR RAILROADS.

Application filed September 24, 1917. Serial No. 192,908.

To all whom it may concern:

Be it known that I, JOHAN SKINDERVIKEN, a subject of the King of Norway, and a resident of the city of Chicago, county of Cook, 5 and State of Illinois, have invented certain new and useful Improvements in Electric Safety Systems for Railroads, of which the following is a specification.

My invention relates to improvements in 10 electric safety systems for railroads of that class which are designed to prevent both head-on and tail-end collisions.

The object of this invention is the production of a safety system of the character 15 mentioned which will be of simple construction, positive and quick-acting in operation, and which will not be susceptible to readily becoming inoperative.

A further object is the production of a system 20 through the medium of which an operator or dispatcher in a station along the track may control the movement of trains within a predetermined distance along the track in either direction from the station, so 25 as to thereby afford means of preventing accident and injury because of wash-outs, spread-rails, or any other condition which might otherwise result in wrecking of a train if the latter were not stopped before reaching 30 the point of danger.

Other objects will appear hereinafter.

With these objects in view the invention consists in the combinations and arrangements of parts hereinafter described and 35 claimed.

The invention will be best understood by reference to the accompanying drawings forming a part of this specification, and in which,

40 Fig. 1 is a diagrammatic representation of the system applied to a double track railroad,

Fig. 2 is a diagrammatic representation of the system applied to a single track railroad,

45 Fig. 3 is a diagrammatic representation of the system applied to a single track railroad, and in addition thereto the mechanism for controlling the travel of trains from a station located along the track,

50 Fig. 4 is a vertical sectional detail illustrating the construction of one of the contact shoes carried by each train,

Fig. 5 is a top plan view of the outer end of the shoe shown in Fig. 4,

55 Fig. 6 is a view similar to Fig. 5 of a con-

tact shoe carried by each train at the side opposite that at which the shoe shown in Figs. 4 and 5 is arranged,

Fig. 7 is a vertical transverse section 60 through a single track railroad equipped with the safety system, the connections with the train and the mechanism located on the latter being shown diagrammatically,

Fig. 8 is a top plan view of one of the contact devices included in the invention 65 which are arranged along the track of the railroad, the top plate of the contact device being removed in order to expose underlying parts,

Fig. 9 is an end view of the contact device 70 shown in Fig. 8,

Fig. 10 is a central vertical transverse section of the contact device,

Fig. 11 is an enlarged detail plan view of 75 one of the switch members provided in the control station arranged along the railroad track,

Fig. 12 is a section taken on line $x-x$ of Fig. 11,

Fig. 13 is a side elevation of the construction shown in Fig. 11,

Fig. 14 is a top plan view of another one of the switch devices provided in the control station, and

Fig. 15 is a side elevation of the construction shown in Fig. 14.

Where the system is employed in connection with a single track railroad, or one where the trains are required to move in both directions, making it necessary to provide against both head-on and tail-end collisions, this arrangement being illustrated in Fig. 2, each train traveling over the track and preferably the locomotive which is shown at A in Fig. 7, is equipped at one side

90 with contact shoes B and C and at its other side with a contact shoe D. The contact shoe B comprises two vertically extending insulated contact members 1 and 1' and the contact shoe C comprises two spaced insulated contact members 2 and 2', said contact members 1 and 1' and 2 and 2' being securely mounted in a tubular body or holder, as shown, which is suitably rigidly fastened to the locomotive. Correspondingly, the shoe D is formed of two spaced insulated contact members 3 and 3' which are suitably mounted in a tubular holder or arm which is suitably fixed to the opposite

95 side of the locomotive. Correspondingly, the shoe D is formed of two spaced insulated contact members 3 and 3' which are suitably mounted in a tubular holder or arm which is suitably fixed to the opposite

100 side of the locomotive. Correspondingly, the shoe D is formed of two spaced insulated contact members 3 and 3' which are suitably mounted in a tubular holder or arm which is suitably fixed to the opposite

105 side of the locomotive. Correspondingly, the shoe D is formed of two spaced insulated contact members 3 and 3' which are suitably mounted in a tubular holder or arm which is suitably fixed to the opposite

110 side of the locomotive. The contact mem-

bers 1 and 1' of the shoe B are connected by means of conductor wires 4 and 5 with a source of electrical energy such as a battery 6 provided in the locomotive. Interposed in 5 the conductor wire 4 is an electro-magnet 7 adapted upon closing of the circuit between contact members 1 and 1' to be energized. Electro-magnet 7 cooperates with a make-and-break device consisting of a movable contact member 8 and a stationary contact 9, the latter being adapted to frictionally engage with the former when said member 8 is moved into engagement therewith. The arrangement is such, as will be seen, that 10 when electro-magnet 7 is energized, the contact member 8 will be moved into engagement with the contact 9 in order to close the circuit therethrough. The contact 8 is connected by means of a conductor wire 10 with 15 the conductor wire 4. The contact 9 is connected by means of a conductor wire 11 with one side of an electric motor 12, the opposite side of said motor being connected by means of a conductor wire 13 with the conductor 20 wire 5. With this arrangement, then it will be seen that, when the contact member 8 is moved through the influence of electro-magnet 7, into engagement with the contact 9, a circuit will be closed through the 25 motor 12 which will cause operation of the latter. The power shaft 14 of the motor 12 is formed with a worm thread as shown, which is adapted to engage with a worm wheel 15 fixed to the stem 16 of a valve 30 interposed in the compressed air pipe 17 of the brake system of the train. The arrangement is such that upon rotation of the shaft 14, the valve stem 16 will be rotated and cause opening of the valve controlled thereby and thus effect setting of the brakes of 35 the train, as will be readily understood by those skilled in the art.

Carried by the worm wheel 15 is a switch arm or blade 18 adapted, when the worm wheel 15 reaches a point in its rotation in 40 which the valve stem 16 is in fully open position, to engage with spaced contacts 19 and 19' in order to close an electric circuit therethrough. The contact 19 is connected 45 by means of a conductor wire 20 with the wire 13, the contact 19' being connected by means of a conductor wire 21 with one side of an electro-magnet 22 which is so arranged that, upon energizing thereof, the member 8 of the make-and-break devices 50 8-9, will be moved to open position. The opposite side of electro-magnet 22 is connected by a conductor wire 23 with the conductor wire 10. With this arrangement, it 55 will be seen that, when the switch member 18 reaches the point in which the same engages with the contacts 19 and 19' a circuit will be closed through make-and-break device 8-9 hence breaking the circuit through 60 the motor 12, with the result of stopping the

latter. Thus, with this arrangement, the motor will be automatically stopped when the valve which is controlled thereby is in fully open position. The motor 12 is pivotally mounted, as at 12', and the outer end of 70 the shaft 14 is releasably locked in operative position by a suitable locking device 14' so as to permit of release of the outer end of said shaft and upward swinging of the same in order to permit the returning of the 75 worm wheel 15 and hence the valve controlled thereby to initial position, after an actuation of the mechanism, the worm wheel being manually operated to return it to its normal position.

Supplemental conductor wires 24 and 25 are connected with the contact members 1 and 1' of the shoe B, and an ordinary switch or push button 26 is located in the locomotive for connecting the wires 24 and 25 and hence 80 the contact members 1 and 1'. With this arrangement, it will be seen that provision is made whereby the brake-setting mechanism located on the locomotive may be readily and expeditiously tested in order to determine whether or not the same is in perfect working order.

The contact members 2 and 2' of the shoe C are connected by means of conductor wires 27 and 28 with conductor wires 10 and 5 95 respectively. With this arrangement, it will be seen that a circuit is formed which permanently connects the contact members 2 and 2' with the source of energy 6, this circuit being broken by the contact members 2 and 2' themselves which, as above described, are insulated from one another. Interposed in the conductor wire 27 is an electric lamp 29 which affords means of visually advising the locomotive engineer whether or not the 100 circuit through the contact members 2 and 2' is completed and unbroken when the outer ends of said contact members engage with other contact devices along the railroad track, which will be presently described.

Similarly, the contact members 3 and 3' of the shoe D are connected by means of conductor wires 30 and 31 respectively, with conductor wires 5 and 27, the arrangement as is apparent, resulting in a permanent 115 electrical connection between the inner ends of contact members 3 and 3' and the source of energy 6. An electric light 32 is interposed in the conductor wire 30 for a reason similar to that above set forth in connection 120 with the lamp 29.

Arranged at intervals along each side of the railroad track, as shown in the diagrammatic illustration of Fig. 2, is a plurality of contact devices adapted for cooperation 125 with the shoes B, C and D of the trains traveling upon said track. Each of the contact devices arranged along the track comprises a housing 33 (see Fig. 8) which is rigidly mounted upon the ties of the track 130

or other suitable support. The member 33 is formed with an inwardly projecting upper portion in the under side of which are provided three spaced longitudinally extending grooves 34, 35 and 36 adapted to accommodate respectively the contact shoes B, C and D of a train traveling along the track, as clearly shown in Fig. 7. Arranged in the groove 34 is a pair of spring contact members 37 and 37' insulated from each other, as shown. Mounted in the groove 35 are two pairs of spring contact members 38 and 38' and 39 and 39' also insulated from each other. Mounted in the groove 36 are spring contact members 40 and 40' insulated from each other in the same manner as the before mentioned contact members. The arrangement is such, that in the travel of a train past one of the contact devices arranged along the track, the members 1 and 1' of the contact shoe B will engage with the contact members 37 and 37', the contact members 2 and 2' of the shoe C will contact first with the contact members 38 and 38' and later with contact members 39 and 39', respectively. At the same time that the shoes B and C are engaging with the contact devices at one side of the track, as just described, the shoe D at the opposite side of the locomotive, will pass through the groove 36 of the contact device directly opposite at the other side of the track and in so doing the contact members 3 and 3' of said shoe will engage with the contact members 40 and 40' of the last mentioned contact device.

Mounted in the housing 33 of each contact device is also a make-and-break device consisting of a movable contact member 41 which is pivoted intermediate its extremities as at 42. One end of the contact member 41 is adapted, in one position, to releasably engage with a stationary contact member 43, being yieldingly held in engagement therewith by friction. Cooperating with each contact member 41 are four electro-magnets 44, 45, 46, and 47, the arrangement being such that when either electro-magnet 45 or 46 is energized, the contact member 41 will be moved into closing position or into engagement with the contact 43, and when either electro-magnet 44 or 47 is energized, the contact member 41 will be drawn out of engagement with the contact member 43 or to open position.

The contacts 37 and 37' of each contact device, are connected by means of conductor wires 48 and 49 with contacts 43 and 42 respectively, so that when the latter is in closed position, the contact members 37 and 37' will be electrically connected and further so that when the contact members 1 and 1' of the shoe B engage with said contact members 37 and 37', with the make-and-break device 41-43 in closed condition, the circuit through the contact members 1 and 1' of

said shoe will be closed with the result of effecting stopping of the passing train, as above described.

The contact members 38 and 38' of each contact device, are connected by means of conductor wires 50 and 51 with the poles of the electro-magnet 47 of the second contact device behind so that in the travel of a train, when the contacts 38 and 38' are engaged with the contact members 2 and 2' of the shoe C, the electro-magnet 47 of the second contact device behind the train will be energized to cause the make-and-break device of this contact device to be opened and thus automatically breaking the circuit through the corresponding contact members 37 and 37'.

The contact members 39 and 39' are connected by means of conductor wires 52 and 53 with the poles of electro-magnet 45 so that in the travel of a train, as the contact members 2 and 2' of the shoe C thereof passes each contact device along the track, and in so doing engages with the contact members 39 and 39' thereof, the corresponding electro-magnet 45 will be energized in order to effect closing of the corresponding make-and-break device 42-43. This make-and-break device will remain closed until the second succeeding contact device is passed by the train in which event the engagement of the contact members 2 and 2' of the shoe C of the train with the contact members 38 and 38' of the last mentioned contact device will effect energizing of the electro-magnet 47 of the first mentioned contact device to automatically open the corresponding make-and-break device, as above described.

Thus, with this arrangement, it will be seen that in the travel of a train along the track, as the same passes each of the contact devices spaced along the track, the make-and-break device thereof will be automatically closed or rendered operative, each being automatically opened or rendered inoperative as the train passes the second succeeding contact device. Thus, with this arrangement, in the event of a second train coming closer to the first train than the distance between three adjacent contact devices, the same will be automatically stopped through engagement of the contact members 1 and 1' of the shoe B thereof with the contact members 37 and 37' of a contact device in which the make-and-break device is closed, or has not yet been rendered inoperative. In practice the contact devices will be spaced apart at say one mile intervals, and so that with this arrangement, it will be impossible for trains traveling on the same track in the same direction to come closer than within two miles of each other. Both sides of the track are correspondingly equipped, as will be seen,

which renders the system operative with trains moving in either direction upon the track.

Cooperating with the contact members 40 and 40' of each contact device are conductor wires 54 and 57 respectively, the former being connected with a conductor wire 55 which extends along the track for connection with the conductor wires 54 of a series of the contact devices, said wire 55 being also connected by means of conductor wires 56 with one pole of the electro-magnets 46 of the various contact devices of the series. The conductor wires 57 of the various contact devices of the series are connected with a wire 58 extending along the track and which also is connected by means of conductor wires 59 with the other pole of each of the electro-magnets 46. The arrangement is such, as will be seen, that when a circuit through any one pair of the contact members 40 and 40' is closed, all of the electro-magnets 46 which are connected in parallel with the corresponding conductor wires 55 and 58 will be energized, with the effect of moving the movable member 41 of the various make-and-break devices to closed or operative position.

With this arrangement, it will be seen that in the travel of a train along the track, as the shoe D thereof passes the first contact device of a series of the latter, (there being four in each series, as shown in Fig. 2 of the drawings), the make-and-break devices of the corresponding contact devices will be instantly rendered operative. This being so when a train passes the first of the contact devices of a series, the make-and-break devices of the three succeeding contact devices, or the three which are ahead of the train, will be rendered operative, with the result that in the event of an on-coming train, or one moving toward the first train, as the on-coming train passes the first of the contact devices in which the make-and-break devices have been rendered operative, as above mentioned, the circuit through the brake-setting mechanism of the latter train will be closed with the result of quickly and automatically bringing the train to a stop. Both sides of the track being similarly equipped, and all trains being correspondingly equipped, each of two trains approaching each other, as just described, will correspondingly affect the other, with the result of bringing both trains to a stop at the same time.

The last contact device of each series of the latter, as just described, is equipped with an additional pair of contact members 60 and 60', as shown in Fig. 2, which are arranged in the groove 36 of the casing 33 of the device, being insulated from each other and constructed the same as the other contact members of the device, above described and as clearly shown in Fig. 8. The contact member 60 is connected by means of a conductor wire 61 with a conductor wire 62 which extends longitudinally of the track, being connected by branch conductor wires 63 with the conductor wires 53 of the contact devices of the series, said conductor wires 53 being connected by means of conductor wire 64 with one pole of the electro-magnet 44 of each of the contact devices. Thus, with this arrangement it will be seen that a direct connection is established between the contact member 60 and one pole of each of the electro-magnets 44 of the series of contact devices. The contact member 60' is connected by means of a conductor wire 65 with a conductor wire 66 extending longitudinally of the track and connected by branch conductor wires 67 with the other pole of each electro-magnet 44 of the series of contact devices. Thus, with this arrangement, it will be seen that as a train passes the last contact device of each series of the latter arranged along the track, the contact members 3 and 3' of the shoe D of the train engaging with the contact members 60 and 60' of said contact device, will effect the closing of a circuit through the contact members 60 and 60' with the result of simultaneously energizing all of the electro-magnets 44 which are connected in parallel with said contacts 60 and 60', thereby simultaneously effecting movement of the movable members 41 of the make-and-break devices of the series to open position, or with the result of rendering said make-and-break devices inoperative. Hence, with the arrangement set forth, it will be seen that provision is made for the prevention of both head-on and tail-end collisions. It should be noted, however, that the structure illustrated in Fig. 2, in order to be effective in avoiding head-on collisions in the first block of each series of blocks, must be arranged so that the separate series of blocks will overlap one another in the manner in which the individual blocks of each series overlap each other, as by connecting the contact members 40 and 40' of the last contact members of the series (right hand travel) to the block next succeeding (right hand travel), by extending the conductor wires 55 and 58 and connecting them with the corresponding wires of the adjacent series. This precaution is, of course, necessary only in connection with a single track railroad where trains move in both directions. However, where the system is to be used in connection with a double track railroad, or where the trains move in only one direction upon each track, the provision of mechanism for the prevention of head-on collisions is unnecessary. Therefore, in double track railroads, the use of electro-magnets 44 and 46, as well as the contact members 40 and 40' and 60 and 60',

together with the conductor wires cooperating with these elements are dispensed with and only so much of the system employed as is instrumental in the prevention of tail-
5 end collisions, as illustrated in Fig. 1, except that in Fig. 1, the electro-magnets 47 are arranged side by side with the electro-magnets 45, instead of directly opposite the latter, as shown in Fig. 2, the arrangement
10 shown in Fig. 1 being identical to the corresponding parts shown in Fig. 2, which has been described in detail.

In order to guard against sleet and rain entering the ends of the grooves 34, 35 and
15 36 of the various contact devices, resilient doors 68 preferably of rubber are provided at the ends of said grooves, as clearly shown in Figs. 9 and 10. These doors normally assume closed positions, being adapted, how-
20 ever, to swing in either direction in order to permit of the passage of the contact shoes B, C and D of the trains.

In order to facilitate the connection of the conductor wires extending longitudinally of the railroad track and the conductor wires cooperating with the contact members and electro-magnets of each contact device, a connection board 69 having a plurality of binding posts thereon is provided in the housing 33 of each contact device, as clearly shown in Fig. 10, an opening 69' being provided in the housing for the passage of the conductor wires, as clearly shown in Figs. 8 and 10. A cable 70 extends
35 along one side of the track to accommodate the longitudinally extending conductor wires cooperating with the track, the branch conductor wires which cooperate with the contact devices at the opposite side of the
40 track being run transversely of the track from said cable, as shown at 71 in Fig. 7.

In Fig. 3 wherein is illustrated mechanism for controlling the movement of trains by manually adjustable mechanism under
45 the control of an operator located in a station along the track, a switch or siding track 72 is illustrated in connection with the main track, this track being employed to accommodate a slow train or freight
50 train in order to permit of the passage of a faster train. Arranged adjacent the track at the switch track 72 is a station 73 diagrammatically illustrated. Arranged in
55 said station for cooperation with the contact devices at each side of the track is a switch device comprising bars 74 and 74' which are slidably mounted in supports 75 and 75' respectively, as clearly shown in Figs. 11, 12 and 13. Springs 76, as clearly
60 shown in Fig. 12 cooperate with the bars 74 and 74' to securely press the latter into engagement with one side of each of the supports 75 and 75' in order to insure a good electrical connection. Pins 77 and 78 co-
65 operate with the bars 74 and 74' to limit

the amplitude of sliding movement of the same. At one end the bars 74 and 74' are connected with a handle 79 insulated from said bars and which affords means of simultaneously sliding the same, said bars 74 and 74' being insulated from each other. Provided upon the bars 74 and 74' are outwardly and downwardly projecting contact flanges 80 and 80', the depending portions of which are inclined as shown. Arranged
70 at the sides of bars 74 and 74' are pairs of spring arms 81 and 82 and 81' and 82' respectively, insulated from each other. At the free ends of said arms 81 and 82 and 81' and 82' are provided upwardly extending contact pins 83 and 84 and 83' and 84' respectively, adapted for engagement with the inner sides of the depending portions of contact flanges 80 and 80' upon forward or withdrawing movement of the handle 79,
75 as will be readily understood. The amplitude of movement of the handle 79 and hence the flanges 80 and 80' is such that, in the movement of said handle to its forward terminals of movement, said flanges will be
80 carried completely past the contact pins 83 and 84 and 83' and 84'. The rearward ends of said flanges are spaced closer together than the pins 83 and 83' and 84 and 84' so that upon the return movement of
85 said contact flanges, said contact pins will engage against the outer sides of the depending portions of said flanges. Said depending portions of said flanges are provided at their outer sides with coverings of
90 insulating material so that electrical connection between the contact pins 83 and 84 and 83' and 84' and the flanges 80 and 80' will be effected only upon forward movement of the latter.

The supports 75 and 75' are connected by means of conductor wires 85 and 85' with the circuit wires 86 and 87 of a battery or source of electrical energy 88 provided in the station 73. The contact members 81 and 81' are connected by conductor wires 89 and 89' with the conductor wires 50 and 51 at the adjacent side of the track which cooperate with the electro-magnet 47 of the contact device second removed from the station to the right (not shown in Fig. 3). The contact members 82 and 82' are connected by means of conductor wires 90 and 90' with the conductor wires 50 and 51 which cooperate with the electro-magnet 47 of the contact device first removed from the station 73 to the right of the latter. Thus, it will be seen that each of the switch devices described is adapted to control the electro-magnets 47 of the two contact devices
115 at either side of the switch track 72 which would be affected by a train which had entered upon the switch track from either end of the latter. It is, of course, understood from the foregoing, that the make-
120

and-break devices of the two contact devices immediately behind a train are always operative or closed, and so that without the provision of the switch mechanism described, in the event of a second or fast train passing the switch track onto which a slower train has been side-tracked, the faster train would be automatically stopped immediately upon passing the first of the two contact devices which had been set or rendered operative by the train which had entered upon the switch track. However, through the provision of the switch mechanism as described, the contact devices, that is the make-and-break devices of the contact devices which had been set or rendered operative by the slow train which entered the switch track, may be opened or rendered inoperative and thus permit of the passage of the faster train without the latter being effected by said contact devices. In the forward movement of the handle 79 of each of the switch devices, bringing the corresponding contact flanges 80 and 80' into engagement with the contact pins 83 and 84 and 83' and 84', it will be seen that the circuit through the two sets of wires 51 with which the wires 89 and 89' and 90 and 90' connect, will be closed through the battery or source of energy 88 and with the result of energizing the magnets 47 with which said two sets of wires 50 and 51 connect. By covering the outer sides of the contact flanges 80 and 80' of the switch devices with insulating material, the return movement of the switch devices is permitted without affecting the condition of the make-and-break devices controlled thereby and which were opened or rendered inoperative through forward movement of the handle 79 of said switch devices.

Provision is also made whereby the operator located in the station 73 may control the travel of a train approaching the station, or which has passed the same, thus making it possible for the operator, upon receiving notice of impending danger to a train which is within the zone or domination of the station 73, to automatically stop a train and thus prevent possible wreck or injury. This is, of course, of advantage in connection with wash-outs, spread-rails or other trouble which might result in wrecking or derailing of a train.

55 This mechanism comprises four switches which are located in the station 73 which are of identical construction and electrically connected with the conductor wires 55 and 58 and 62 and 66 at either side of the track and extending in either direction from the station along the track. Each of the last mentioned switches (see Fig. 14) consists of a pair of switch bars 91 and 91' which are mounted in supports 92 and 92' in precisely the same manner as the switch bars

74 and 74' are mounted in the guides 75 and 75'. The forward ends of bars 91 and 91' are connected with the handle 73 from which the same are insulated. Upon the bars 91 and 91' adjacent the forward ends thereof are provided outwardly projecting rounded contact lugs 94 and 94' which are adapted, upon forward movement of the handle 73 to successively engage with spring contact members 95 and 96 and 95' and 96' arranged at opposite sides of the movable switch element.

The supports 92 and 92' are connected by conductor wires 97 and 97' with the circuit wires 86 and 87 respectively of the battery or source of energy 88 so that when the contact lugs 94 and 94' engage with the contact members 95 and 95', the latter will be electrically connected with the source of energy 88, and similarly when said contact lugs engage with the spring contacts 96 and 96', a circuit will be closed through the same and the source of energy 88. The contact members 95 and 95' of each switch are connected by means of conductor wires 98 and 98' with the conductor wires 66 and 62 respectively, leading to the adjacent contact device. The contact members 96 and 96' of each switch are similarly connected by means of conductor wires 99 and 99' with the conductor wires 55 and 58 leading to the adjacent contact device. With this arrangement then, it will be seen that in the forward movement of the movable element of each of said switches, when the contact lugs 94 and 94', engage with the contact members 95 and 95' the electro-magnets 44 with which the corresponding conductor wires 62 and 66 are connected will be energized and thus cause opening of the corresponding make-and-break devices. Upon contact of said lugs 94 and 94' with the contact members 96 and 96', the electro-magnets 46 with which the conductor wires 55 and 58 are electrically connected, will be energized and cause closing of said make-and-break devices or render the same operative. Hence, with this arrangement, upon outward movement of the movable switch elements of the last described switch devices, the make-and-break devices within a predetermined distance in either direction from the station may be closed or rendered operative in order to automatically effect the stopping of any train which may pass any of the contact devices in which the make-and-break devices have been closed or rendered operative. The zone of influence of the operator located at the station may, of course, be extended to any extent desired by simply connecting the conductor wires 55 and 58 and 62 and 66 with the electro-magnets 46 and 44 of a greater or less number of the contact devices arranged along the track. Upon the return movement of the movable switch members

of said switches, the contact lugs 94 and 94' being brought into contact with the contact members 95 and 95' last in this movement, or after said contact lugs have left 5 the contact members 96 and 96', the electromagnets 44 will be the last to be energized in this movement of said switch elements, and hence will effect opening of the make-and-break device or rendering of the same 10 inoperative in the return movement of said movable switch members.

While I have illustrated and described the preferred forms of construction for carrying my invention into effect, these are capable of 15 variation and modification without departing from the spirit of the invention. I, therefore, do not wish to be limited to the precise details of construction set forth, but desire to avail myself of such variations and 20 modifications as come within the scope of the appended claims.

Having described my invention what I claim as new and desire to secure by Letters Patent is:

25 1. In an electric safety system for railroads, the combination of a worm wheel on each train; a motor having a shaft provided with a worm thread adapted to mesh with said wheel; a valve interposed in the air 30 brake system of the train operable upon the rotation of said wheel; a plurality of electrical devices spaced along the track, each of which is adapted, when in operative condition, to effect rotation of said wheel of a 35 train passing the same; electrical means on each train for rendering operative certain of said electrical devices along the track; electrical means on each train for subsequently rendering inoperative the last mentioned devices after the train has traveled 40 a predetermined distance; a station located along the track; and means in said station for co-operation with certain of said electrical devices along the track for rendering 45 the same operative or inoperative at the will of the operator located in the station, substantially as described.

2. In an electric safety system for railroads, the combination of a worm wheel on 50 each train; a motor having a shaft provided with a worm thread adapted to mesh with said wheel; a valve interposed in the air brake system of the train operable upon the rotation of said wheel; a plurality of 55 electrical devices spaced along the track, each of which is adapted, when in operative condition, to effect rotation of the worm wheel of a train passing the same; electrical means on each train for rendering operative certain of 60 said electrical devices along the track; electrical means on each train for subsequently rendering inoperative the last mentioned devices after the train has traveled a predetermined distance; a station located along the track; and means in said 65

station for co-operation with the electrical devices located adjacent said station at either side thereof for rendering the same operative or inoperative at the will of an operator located in the station, substantially as described. 70

3. In an electric safety system for railroads, the combination of a worm wheel on each train; a motor having a shaft provided with a worm thread adapted for meshing with said wheel; a valve interposed in the air brake system of the train operable upon the rotation of said wheel; a normally open electric circuit on each train, adapted, when closed, to effect rotation of said wheel; a plurality of make-and-break devices spaced along the track, each of which is adapted, when actuated, to close the mentioned circuit of a train passing the same; means on each train for effecting opening and closing of said make-and-break devices; a station located along the track; and means in said station for co-operation with certain of said make-and-break devices along the track for opening and closing the same at the will of an operator located in the station, substantially as described. 80

4. In an electric safety system for railroads, the combination of a worm wheel on each train; a motor having a shaft provided with a worm thread adapted to mesh with said wheel; a valve interposed in the air brake system of the train operable upon the rotation of said wheel; a normally open electric circuit on each train adapted, when closed, to effect rotation of said wheel; a plurality of make-and-break devices spaced along the track, each of which is adapted, when actuated to closed condition, to close the mentioned circuit of a train passing the same; means on each train for effecting opening and closing of said make-and-break devices; a station located along the track; and means in said station for co-operation with the make-and-break devices adjacent said station at either side thereof for opening and closing the same at the will of an operator located in the station, substantially as described. 95

5. In an electric safety system for railroads, the combination of a worm wheel on each train; a motor having a shaft provided with a worm thread adapted to mesh with said wheel; a valve interposed in the air brake system of the train operable upon the rotation of said wheel; a plurality of electrical devices spaced along the track, each of which is adapted, when in operative condition, to effect rotation of said wheel of a train passing the same; electrical means on each train for rendering operative certain of said electrical devices along the track; electrical means on each train for subsequently rendering inoperative the last mentioned devices after the train has traveled a predetermined distance. 100

terminated distance; and manually operable means independent of the train adapted for cooperation with certain of said electrical devices for rendering the same operative or 5 inoperative at the will of the operator, substantially as described.

6. In an electric safety system for railroads, the combination of a worm wheel on each train; a motor having a shaft provided 10 with a worm thread adapted to mesh with said wheel; a valve interposed in the air brake system of the train operable upon the rotation of said wheel; a normally open electric circuit on each train adapted, when 15 closed, to effect rotation of said wheel; a plurality of make and break devices spaced along the track, each of which is adapted, when in closed condition, to close the mentioned circuit of a train passing the same; 20 means on each train for effecting opening and closing of certain of said make-and-break devices during travel of the train; and manually operable means independent of the train adapted for co-operation with certain of said make-and-break devices for 25 operating or closing the same at the will of the operator, substantially as described.

7. In an electric safety system for railroads, the combination of a worm wheel on 30 each train; a motor having a shaft provided with a worm thread adapted to mesh with said wheel; a valve interposed in the air brake system of the train operable upon the rotation of said wheel; a plurality of electrical devices spaced along the track, each 35 of which is adapted, when in operative condition, to effect rotation of the worm wheel of a train passing the same; electrical means on each train for rendering operative certain 40 of said electrical devices along the track; and a manually operable switch co-operating with an independent source of energy independent of the train adapted for co-operation with certain of said electrical devices 45 for rendering the same operative or inoperative at the will of the operator, substantially as described.

8. In an electric safety system for railroads, the combination of a worm wheel on 50 each train; a motor having a shaft provided with a worm thread adapted to mesh with said wheel; a valve interposed in the air brake system of the train operable upon the rotation of said wheel; a normally open electric circuit on each train adapted, when 55 closed, to effect rotation of said wheel; a plurality of make-and-break devices spaced along the track, each of which is adapted, when in closed condition, to close the mentioned circuit of a train passing the same; means on each train for effecting opening and closing of certain of said make-and-break devices during travel of the train; and manually operable switches co-operating 60 with a source of energy independent of

the train adapted for co-operation with said make-and-break devices for opening or closing the same at the will of the operator, substantially as described.

9. In an electric safety system for railroads, the combination of a worm wheel on each train; a motor having a shaft provided 70 with a worm thread adapted to mesh with said wheel; a valve interposed in the air brake system of the train operable upon the rotation of said wheel; a plurality of electrical devices spaced along the track each 75 of which is adapted, when in operative condition, to effect rotation of the worm wheel of a train passing the same; electrical means on each train for rendering operative certain 80 of said electrical devices along the track; and a manually operable switch co-operating with an independent source of energy independent of the train adapted for co-operation with certain of said electrical devices for rendering the same operative or 85 inoperative at the will of the operator, each of said switches comprising a movable element adapted, when moved to one position, to render said electrical devices inoperative and, when moved to another position, to render 90 said devices operative, substantially as described.

10. In an electric safety system for railroads, the combination of a worm wheel on each train; a motor having a shaft provided 95 with a worm thread adapted to mesh with said wheel; a valve interposed in the air brake system of the train operable upon the rotation of said wheel; a plurality of electrical devices spaced along the track, each 100 of which is adapted, when in operative condition, to effect rotation of the worm wheel of the train passing the same; electrical means on each train for rendering operative certain 105 of said electrical devices along the track; electrical means on each train for subsequently rendering inoperative the last mentioned devices after the train has traveled a predetermined distance; manually operable means independent of the train adapted for co-operation with certain of said electrical devices for rendering the same inoperative after having been rendered operable 110 through passing of a train, said means comprising a movable switch element adapted, when moved in one direction, to render said devices inoperative; and means for rendering ineffective the return movement of said switch element, substantially as described.

11. In an electric safety system for railroads, the combination with a main track and a side track connected therewith, of a worm wheel on each train; a motor having a shaft provided with a worm thread adapted to mesh with said wheel; a valve interposed in the air brake system of a train operable 115 upon the rotation of said wheel; a plurality 120

- of electrical devices spaced along the track, each of which is adapted, when in operative condition, to effect rotation of the worm wheel of a train passing the same; means on 5 each train for rendering operative each of said electrical devices passed thereby; means on each train for subsequently rendering inoperative each of said devices after the train has traveled a predetermined distance; and 10 manually controlled means independent of the trains adapted for rendering inoperative the electrical devices rendered operative by a train passing onto said side track and which has remained in this closed condition after 15 the passage of the train onto the side track, substantially as described.
12. In an electric safety system for railroads, the combination of a main track and a side track connected therewith, of a worm 20 wheel on each train; a motor having a shaft provided with a worm thread adapted to mesh with said wheel; a valve interposed in the air brake system of the train operable upon the rotation of said wheel; a normally 25 open electric circuit on each train adapted,
- when closed, to effect rotation of said wheel; a plurality of make-and-break devices spaced along the track, each of which is adapted, when actuated to closed condition, to close the mentioned circuit of a train passing the 30 same; means on each train for effecting closing of each make-and-break device passed thereby; means on each train for subsequently effecting opening of each make-and-break device after the train has traveled a 35 predetermined distance; and manually controlled means independent of the trains adapted for opening the make-and-break devices closed by the passage of a train onto said side track and which has remained in 40 this closed condition after the passage of the train onto the side track, substantially as described.
- In testimony whereof I have signed my name to this specification in the presence of 45 two subscribing witnesses.

JOHAN SKINDERVIKEN.
